F. W. SCHROEDER,
INCANDESCENT GAS BURNER,
APPLICATION FILED MAY 4, 1918.

1,320,281.

Patented Oct. 28, 1919.

UNITED STATES PATENT OFFICE.

FREDERICK WILLIAM SCHROEDER, OF LONDON, ENGLAND.

INCANDESCENT GAS-BURNER.

1,320,281.

Specification of Letters Patent. Patented Oct. 28, 1919.

Application filed May 4, 1918. Serial No. 232,515.

To all whom it may concern:

Be it known that I, FREDERICK WILLIAM SCHROEDER, a subject of the King of Great Britain, residing in London, England, have 5 invented certain new and useful Improvements in Incandescent Gas-Burners, of which the following is a specification.

My invention relates to an inverted incandescent gas burner of the kind comprising 10 a gas and air mixing device, a burner nozzle piece and an annular holder or ring for an inverted mantle, which holder is supported from the nozzle piece by means of interengaging lugs on the nozzle and holder. It 15 consists in improvements which have for their object to produce greater brilliancy of light than has been possible heretofore by attaining a more perfect combustion by retaining as much heat as possible around the 20 nozzle piece in order to heat thoroughly the mixture of air and gas passing from the gas and air mixing device, before it strikes the mantle. To these ends I construct the burner in such a manner that the mixing of 25 the gas and air is effected in stages, and I so arrange the burner nozzle piece and mantle that the passage-way or clearance, usually existing in known constructions of inverted incandescent gas burners between 30 the side wall of the nozzle piece and the inner peripheral wall of the mantle holder, is much restricted for the purpose of retaining heat within the mantle and around the nozzle piece as long as possible so that 35 the latter becomes heated, thereby causing a more perfect combustion than hitherto.

The improvements, which include improved forms of the mixing device, nozzle piece and mantle holder, will be described 40 with reference to the accompanying drawing in which Figure 1 is a sectional elevation of the improved burner showing the improved mixing device and one form of the improved nozzle piece and mantle holder; Fig. 2 is an elevation of the burner nozzle piece and mantle holder shown in Fig. 1; Fig. 3 is a section showing a modified arrangement, wherein the mantle holder is supported from the nozzle piece by means 45 of a separate sleeve piece or yoke; Fig. 4 is a plan view of the nozzle piece shown in Fig. 3; and Fig. 5 is a plan of the improved mantle holder. In the several figures the same parts are distinguished by the same 50 letters.

Fig. 1 shows the arrangement for effect-

ing the mixing of the gas and air in stages. As there shown a portion of the air necessary for perfect combustion mixes with the gas as the latter enters a Bunsen-like tube 60 *a*, located in a mixing chamber *b*, from the gas supply pipe *c*. A further quantity of air is allowed to mix with the first mixture as the latter issues from the mouth of the Bunsen tube *a* and a still further quantity 65 of air is added to the said last mixture as this mixture issues at the mouth of the mixing chamber *b* and enters a mixing tube *i*. The final mixture of gas and air passes along the tube *i*, which is appropriately bent, 70 to the nozzle piece *j*.

The terminal portion of the mixing chamber in proximity to the Bunsen tube *a* is inclosed in a chamber *f* formed by a casing *e* which at its upper end is attached to the 75 upper end of the mixing chamber *b* and at its lower end is formed with an inwardly projecting flange *e'* so as to leave a restricted annular passage *g*, between it and the chamber *b*, through which passage air is 80 able to enter chamber *f*. Air thus admitted to chamber *f* enters chamber *b* through openings *b'* in its side wall. Of the air entering chamber *b* some of it enters the tube *a* through openings *a'* in the side of the Bunsen tube *a*, while some, flowing upwardly, 85 joins the mixture of gas and air issuing at the end *a''* of the Bunsen tube. The mixture thus formed flows upwardly through the mixing chamber *b*, which in its upper portion is contracted to form a preliminary 90 mixing tube *b'*. Issuing at the mouth *b''* of the preliminary mixing tube *b'* the mixture enters the mixing tube or arm *i*. The remaining portion of the requisite air to be 95 mixed with the gas can be added to the mixture as it thus enters tube *i*. The remaining portion of air may be conveniently admitted by means of passages *h* formed by indenting or corrugating the wall *b''* of the reduced 100 upper portion *b'* of the mixing chamber *b*.

The burner nozzle piece *j*, which may be of porcelain or any other appropriate substance, is, as in some known burners, of a shape that is conical at its lower or exit end 105 and cylindrical at its other or admission end. It is screwed or otherwise suitably attached to the arm *i*, which in practice would be so arranged that the nozzle piece *j*, or a globe encircling it, would be in close proximity 110 to the wall *e* of chamber *f* in order to heat that chamber and the air within it. The

nozzle piece is provided according to this invention with a projecting flange j' which serves to support the mantle holder or ring k . In the arrangement shown in Figs. 1 and 5, 2, a number of L shape lugs j^2 depend from the flange j' being integrally formed therewith. The improved mantle holder or ring is formed with outside lugs only. These lugs k' which correspond in number with lugs j^2 , extend upwardly and outwardly, so that when the holder is passed or threaded over the outlet or lower end of the nozzle piece j , the lugs k' can, by turning the holder, be made to engage, in bayonet-like 10 fashion, with the lugs j^2 .

The bore of the mantle holder k is such that its internal periphery fits snugly around the lower or cylindrical portion of the nozzle piece, but its internal peripheral wall is provided with a series of shallow grooves or corrugations, such as k^2 , Fig. 5, for the passage of the heated products of combustion which escape slowly through the grooves k^2 from the space within the mantle l thereby 20 heating the nozzle piece which therefore acts also as a chamber for heating the mixture of gas and air passing therethrough from the tube i .

In the arrangement shown in Figs. 3, 4 and 5, the lugs k' on the mantle holder engage with lugs m' formed on a separate sleeve piece m , which may be formed of metal or other suitable substance, and is adapted to fit upon the flanged portion j' of the nozzle piece j . Suitable means are provided for preventing the sleeve m turning around when the mantle holder on being slipped over the end of the nozzle piece is turned in a manner to cause lugs k' to engage with lugs m' on the sleeve piece. For instance the nozzle piece j may be provided with slots j^3 into which the depending lugs m' on the sleeve can be inserted or placed to prevent rotation of the sleeve. 30

45 Since the improved annular mantle ring is devoid of internal projections or lugs, it is possible to use such mantle ring also with upright mantle burners.

Having thus fully described the nature 50 of my said invention and the best means I know of carrying the same into practical effect, I claim:—

1. An inverted incandescent gas burner comprising, in combination, a burner nozzle 55 and a gas air mixing device arranged to admit air in three stages, said device comprising, in combination, a gas supply nozzle, a Bunsen tube encircling the outlet end of said nozzle and having apertures in its side wall, an open-ended tubular casing having laterally disposed openings, said casing arranged to surround the Bunsen tube and having its lower end fixed thereto, and its upper end constituting an outlet end, a second open-ended tubular casing having one 60

end fixed to the first casing and the other end provided with an inwardly projecting flange encircling the fixed end of the first casing and forming therewith a restricted annular passage open to the atmosphere, 70 whereby air entering the passage passes through the said apertures into the first said casing, a portion of said air flowing through the said openings and mixing with gas issuing from the outlet of the gas supply nozzle, 75 the remaining portion of air commingling with the gas and air issuing from the outlet of the Bunsen tube, and a mixing tube having one end connected with the Bunsen burner nozzle and the other end overlapping 80 the second end of the first said tubular casing and forming therewith channels open to the atmosphere, whereby air entering through the channels unites with the mixture of air and gas issuing from the outlet 85 of the last said casing.

2. An inverted incandescent gas burner comprising in combination a gas and air mixing device arranged to admit air to the mixing device in a plurality of stages, said device comprising in combination a gas supply nozzle, a Bunsen-tube encircling said nozzle and having air inlet apertures in its side wall, an open-ended tubular casing having laterally disposed air inlet openings, 95 said casing surrounding the Bunsen tube and having one end fixed thereto, a second open-ended casing, one end thereof fixed to the first casing, and the second end provided with an inwardly projecting flange encircling the fixed end of the first casing and forming therewith a restricted annular air inlet passage, and a mixing tube having one end overlapping the second end of the tubular casing and forming therewith passages for 100 admitting air to said tube and means for heating the gaseous mixture before it is ignited or burnt, said heating means consisting of a downwardly directed burner nozzle piece supported from the second end 105 of the mixing tube and having a cylindrical body part, a number of downwardly extending L-shaped lugs carried by the nozzle piece, and an annular mantle holder encircling the said body part of the nozzle piece 110 and having a number of upwardly and outwardly extending lugs detachably and cooperatively engaging the said downwardly extending lugs, the inner peripheral wall of the holder being formed with a plurality of 115 shallow grooves for the passage of heated products of combustion.

3. An inverted incandescent gas burner comprising in combination a gas and air mixing device arranged to admit air to the mixing device in a plurality of stages, said device comprising in combination a gas supply nozzle, a Bunsen-tube encircling said nozzle and having air inlet apertures in its side wall, an open-ended tubular casing hav- 125

ing laterally disposed air inlet openings, said casing surrounding the Bunsen tube and having one end fixed thereto, a second open-ended casing, one end thereof fixed to the 5 first casing, and the second end provided with an inwardly projecting flange encircling the fixed end of the first casing and forming therewith a restricted annular air inlet passage, and a mixing tube having one 10 end overlapping the second end of the tubular casing and forming therewith passages for admitting air to said tube and means for heating the gaseous mixture before it is ignited or burnt, said heating means consisting of a downwardly-directed burner 15 nozzle piece supported from the second end of the mixing tube and having a cylindrical body part and a number of integrally

formed downwardly extending L-shaped lugs, and an annular mantle holder encircling the said body part of the nozzle piece and having a number of upwardly and outwardly extending lugs detachably and cooperatively engaging the said downwardly extending lugs, the inner peripheral wall of 20 the holder being formed with a plurality of shallow grooves for the passage of heated products of combustion.

In testimony whereof I have signed my name to this specification in the presence of 30 two subscribing witnesses.

FREDERICK WILLIAM SCHROEDER.
